APPARATUS FOR GRINDING AND TREATING WIRE CLOTHED ROLLERS

Application filed December 21, 1928, Serial No. 327,544, and in Great Britain March 3, 1928.

Cylinders and rollers clothed with saw tooth wire are well known in the textile trade and it is common practice to true the wire, as also to grind the wire clothing and to burnish 5 in separate machines.

So far as I am aware it is not however known to grind and burnish such saw tooth wire in a single one machine, and the present invention contemplates a machine wherein 10 both grinding and burnishing can be effected as successive operations in the one and the same machine.

I propose to construct a machine which will be capable of performing both these operations upon a saw-tooth wire-covered roller and which machine affords facility in getting the clothed roller into position and in removing it.

The important novelty, quite apart from 20 the complete construction, lies in the use of a head wherein can be carried the traversing grinding mechanism and also the burnishing mechanism each settable to the saw tooth wire covered roller, while the burnishing mechanism can be instantly lowered to any set 25 position, and readily elevated clear out of the way for the introduction or removal of a saw-tooth wire-clothed roller. Further, there is provided a circular setting motion to 30 regulate the operative action of the grinding mechanism and the burnishing mechanism which are controlled from and operate about a common centre.

For the purpose of fully disclosing the invention, I shall now describe the same with 35 the help of the accompanying drawings, wherein:

Fig. 1 is an end elevation from the left-hand end of the machine.

Fig. 2 shows an end elevation from the right-hand end, and,

Figs. 3 and 3a together illustrate a broken front elevation of the machine.

Fig. 4 is a detail sectional view on an enlarged scale, taken on the line IV—IV of Fig. 1.

Referring to the drawings, a , a' designates the end standards of the machine, which end standards are connected by a main cross rail a^2 upon which are secured a pair of

bearing brackets b in which is mounted for rotation the axle r' carrying the usual saw-tooth, wire-clothed roller r . The axle is removably held in its bearings by a pair of bearing caps b' , which are perforated at 55 their opposite ends to permit the passage therethrough of a pair of threaded studs b^2 carried by the bearing brackets, the caps being maintained in position by a pair of knurled nuts b^3 threaded on the studs b^2 . The 60 roller r may be driven by a belt r^2 passing over a pulley r^7 secured on the axle r' , said belt receiving its motion from a second pulley r^3 secured to the shaft of a chain wheel r^4 over which passes a chain r^5 , said chain receiving motion from a second chain wheel r^6 secured on a driving shaft s . A guard r^7 65 may be provided for the chain r^5 . It will be obvious that the roller may be driven in any other convenient manner.

Secured on the end standards a , a' at opposite ends of the machine are a pair of supporting brackets c , each of which is provided on its outer surface with an annular boss or flange c' , best shown in Fig. 4, which flange 70 is engaged by a similar flange formed on a circular disc c^2 , said discs being each partly rotatable around a central pivot c^3 secured in the supporting brackets c . Each of the discs c^2 is provided on its periphery with a few teeth c^4 in mesh with a pinion c^5 secured on a shaft c^6 which extends longitudinally through the machine. Secured on the shaft c^6 adjacent to each of said pinions c^5 75 is a quadrant c^7 provided on its periphery with worm gear teeth in mesh with a worm c^8 secured on a shaft c^9 having at its outer end a hand-wheel c^{10} for affording manual rotation of the shaft in a manner similar to the gear well known in connection with setting motions for card grinding machines. From this description it will be seen that 80 when the hand wheel c^{10} is rotated in one or the other directions such rotation will be transmitted to the discs c^2 so that the mechanism associated therewith as hereinafter described will be operated.

Suspended from the pivots c^3 of the discs c^2 are a pair of pendent bracket arms or bearing plates d , each of which is secured to 100

its comparison disc by a bolt d' passing through an elongated perforation in the arm and secured in the disc, (see Fig. 2), whereby the arm is capable of slight angular adjustment with relation to the disc. The bracket arms d are provided at their lower ends with hook-shaped portions d^2 forming bearings for a shaft e' on which is secured the traversing grinding roller e and a differential motion e^2 . This differential motion is of well known construction, it having been shown in my prior Patents Nos. 500,322 and 1,785,731.

It will be obvious from the foregoing that when the discs c^2 are rotated in one direction the lower ends of the arms d will be moved toward the saw-toothed wire-covered roller r thus carrying the traversing grinder e into contact with said roller, whereas rotation of the discs in the opposite direction will carry the grinder out of contact with the saw-tooth roller.

One of the objects of the invention is to provide burnishing means so disposed and operated relatively to the grinding roller e , that, in the normal operation of the device, the motion which carries the grinding roller e out of contact with the saw-tooth, wire-clothed roller r will carry the burnishing means into contact with said saw-tooth roller, and vice versa, means being also provided whereby both the grinding roller and the burnishing means may be carried out of contact with the saw-tooth, wire-clothed roller thereby to permit the ready removal of said roller from its bearings and its replacement therein. To this end I mount on pivot studs or centres $c3$, and at the rear faces of the circular discs or large wheels $c2$, brackets h , h' whose fulcrum is on the pivot studs. One of these brackets h is a plane type, and provided with an opening for the reception of a bearing g' for one end of the axle of a burnishing brush or roller g , while the other bracket h' has secured thereto a bridging-piece $h2$ which projects laterally over a circular disc $c2$ at the end where the operator controls. This bridge piece $h2$ has a curved slot $h3$ concentric with the circular disc $c2$ and lying in a plane parallel to the face of the latter.

The brackets h and h' in addition to being mounted on the fixed studs or centres $c3$ are also mounted on and pinned to an independent shaft $j2$ disposed in axial alignment with the studs $c3$, each end of which shaft $j2$ extends part way through the fulcrum hubs $h9$ of the brackets h and h' (see Fig. 4). The portions of the hubs $h9$ into which the ends of the shaft $j2$ do not penetrate obviously form bearings to fit closely the shaped inner extremities of the studs or centres $c3$. This combination ensures a rigid interconnection between the brackets h , h' and a stiffening of the structure on this axial line.

To return to the bridge-piece $h2$ and the slot therein marked $h3$. There is a stud $h4$ extending laterally from the circular disc $c2$ through said slot $h3$, and clamping provision in the form of a nut $h5$ threaded on said stud and having a lengthened rod or bar $h6$, by which the bridging structure $h2$ and bracket h' can be clamped at any time so as to fix the relative disposition of the burnishing brush or roller g to the traversing grinder e . Releasing of the clamping nut $h5$ will allow the bridging piece $h2$ and interconnected brackets h' , h to become movable a distance governed by the length of the slot $h3$. In order that a definite downward movement of the burnishing brush or roller g can be counted on or arranged for, I provide a milled headed graduating screw $h7$ in the bridging piece $h2$ which can be set as to its lower extremity to the stud $h4$ in the curved slot $h3$ so that even if the clamping nut $h5$ be released the burnishing brush or roller g cannot fall or move beyond the regulated amount (governed by the position of the graduated screw $h7$). Thus, the "set" of the burnishing brush or roller g can be governed with respect to the disposition of the traversing grinder e . This is in spite of the fact that, on releasing the nut $h5$, the burnishing brush or roller g can be lifted by grasping the handle $h8$ and rotating the bracket h' on its pivot the full remaining range of the slot $h3$ thereby to permit removal or introduction of the saw-tooth wire clothed roller r to be dealt with.

The "opening" or lifting of the burnishing brush or roller g as above stated gives free and unrestricted facility for introduction or removal of the saw-tooth wire-clothed roller r and the burnishing brush or roller g can be held open or elevated by tightening the clamping nut $h5$. When the said roller r is in place, the burnishing brush or roller g can be lowered to the desired position by releasing the nut $h5$ and setting the graduated screw $h7$. The relative disposition of traversing grinder and burnishing brush or roller is thus under full control at all times. If the actuating hand-wheel $c10$ is operated in one direction, then the traversing grinder e comes into action on the roller r . On completion of the grinding, then by turning the hand-wheel $c10$ in the opposite direction, the traversing grinder e is moved away from the roller r and the burnishing brush or roller g comes into action. The burnishing brush or roller group has combined therewith a traverse motion as indicated at i in Fig. 3, the link connection i' being pivoted to a lug depending from the bearing $g2$ for the shaft of the burnishing brush or roller g . Such traversing motions are well known in the art and it is therefore believed that further description herein is unnecessary.

There is preferably provided a curved

sheet metal guard *j* for the burnishing brush or roller *g*, which guard *j* is carried on arms *j'*, *j'*, said arms having hubs or sleeves *j3* fitting the shaft *j2*, as indicated in broken lines in Figs. 3 and 3a. As a result when the brackets *h*, *h'* move and carry the burnishing brush or roller down or up the guard *j* moves along therewith, being supported from the shaft *j2* which moves with the brackets *h*, *h'*.

10 The movable bracket structure *h'* at the manipulating end of the setting motion, as hereinbefore stated, is provided with a handle *h8* by which to raise and lower the burnishing brush or roller mechanism when the clamping nut *h5* is released.

15 The manner of driving the traversing grinder *e* and the burnishing brush or roller *g* can be varied, but I propose to use a double V leather link belt, indicated by the line *k* in Figs. 1 and 2. This belt passes from the grooved pulley *k1* on the main driving shaft *s* upwards over a grooved pulley *k4* on a pivoted weighting compensating bracket *k5* fulcrumed at *k6*, then partly around a grooved pulley *k3* on the axle of the burnishing brush or roller *g* and then around a portion of the periphery of a grooved pulley *k2* on the traversing grinder axle *e'* and so down again to the grooved pulley *k1* on the main shaft *s*.

20 This drive compensates for the necessary settings or adjustments of the traversing grinder *e* and the burnishing brush or roller *g*.

25 The action of the machine is such, that the traversing grinder *e* grinds from the point to the back of the teeth and therefore does not spoil the point or effective edge and leaves any burr at the back of the tooth and consequently the burnishing brush or roller can remove these burrs on the long edges of the teeth. I find these burrs can be readily removed from the long edges of the teeth by the burnishing brush or roller *g*.

30 Rollers can be ground and burnished very effectively and expeditiously by the new machine.

The device marked *D* is the known dressing attachment which is traversed to dress the saw-tooth wire clothing by the engagement of its dressing tool or tools with said wire.

35 It is also to be understood that rollers or cylinders clothed with saw-tooth wire and of various diameters, and lengths, can be operated on by adjusting and setting the brackets, and their supports, on and in connection with the bed of the machine, all of which is known.

40 The mode of operation of the apparatus is as follows: The saw-tooth roller *r* is supported by its axle *r1* in the bearing brackets and the removable caps *b1* placed in position on the studs *b2* and the clamping nuts *b3* tightened thereon. The dressing device *D* is then adjusted as to its known tools between

the ranks of saw-tooth wire on roller *r* so that when the roller is driven by belt *r2*, the saw-tooth tools are traversed and the wire is dressed. After dressing the device *D* can be backed off by rotating the screw *D'* anti-clockwise. Thereafter, the teeth of the saw-tooth wire are ground by the known traversing grinder *e* which is moved into contact with roller *r* by operating the hand wheel *c10* as hereinbefore described. After the teeth have been sufficiently ground, the hand wheel *c10* is rotated in the opposite direction thereby to swing the grinder back or out of action and simultaneously carry the burnishing brush *g* into contact with the teeth of roller *r* to burnish them as hereinbefore described. On completion of the burnishing operation, the brush may be moved back by again reversing the rotation of the hand wheel, whereupon the bar *h6* may be lifted to release the nut *h5*, and the operator may grasp the handle *h8* and raise the burnishing brush as far as the stud *h4* and slot *h3* will permit, whereupon the finished roller *r* may be removed and another inserted.

I declare that what I claim is:

1. An apparatus for grinding and burnishing saw-tooth wire on rollers, comprising a framework, adjustable means mounted thereon for carrying a roller to be operated upon, driving means for the roller, brackets supported on said frame, a movable head mounted for rotation on said brackets, a grinding device pivoted for bodily movement concentric with said head and rotatable about its own axis, means for traversing and driving said grinding device, a burnishing brush movably supported on concentric relation to said head, means for adjusting the brush angularly with relation to the head, means for driving said burnishing brush, manually operable means for moving the brush supports, and manually operable gear mechanism associated with said head for rotating the same thereby to bring the grinding device and burnishing brush alternately into action on said roller.

2. An apparatus for grinding and burnishing saw-tooth wire on rollers, comprising means for removably supporting for rotation a roller to be operated upon, means for driving said roller, a movable head pivotally supported in juxtaposition to said roller, a grinding device supported for rotary and axial movement at one extremity of the movable head, means for driving and traversing said grinding device, a burnishing device supported in movable brackets in the movable head, means for adjusting said brackets angularly with relation to the head, means for clamping the brackets in adjusted positions, means for driving the burnishing device, and manually operable gearing associated with the head for bringing the grinding device and the burnishing device into action alternately.

3. An apparatus for grinding and burnishing saw-tooth wire on rollers, comprising means for removably supporting for rotation a roller to be operated upon, means for driving said roller, a movable head pivotally supported in juxtaposition to said roller, gearing for actuating said head, supports pivoted concentrically with the head and carrying a rotatable and axially movable grinding device, means for traversing and driving said grinding device, brackets adjustable angularly with relation to said movable head, means for clamping said brackets in any adjusted position, a burnishing device carried in said brackets, means for driving said burnishing device, and means for supporting the movable head in one position during grinding and in another position during burnishing.
4. An apparatus for grinding and burnishing saw-tooth wire on rollers in a single apparatus, comprising adjustable supports for the roller to be acted on, means for driving said roller, a pivotally mounted head supported in juxtaposition to said roller, adjustable brackets mounted for pivotal movement concentric with said head, a grinding device carried by the head and mounted for rotary and axial movement, means for traversing said grinding device, a burnishing brush mounted for rotation in said brackets, means for driving said grinding device and burnishing brush, manually operable gearing associated with said head for bringing the grinding device and the burnishing brush into operation alternately, and means for adjusting and clamping the brackets in any adjusted position with relation to the movable head.
5. An apparatus for grinding and burnishing saw-tooth wire on rollers, comprising means for supporting and driving a roller in position to be operated on, a head pivotally supported in juxtaposition to said roller, supporting brackets mounted for adjustment on said head, manually operable gearing engaging said head for actuating the same, a rotatable and axially movable grinding device supported for bodily movement about the axis of said head, means for traversing said grinding device, a burnishing device mounted for rotation in said supporting brackets, means for driving said grinding and burnishing devices, means for adjusting said brackets and clamping them in adjusted positions, disengageable brackets permitting ready removal or insertion of the saw-tooth wire roller, and means for holding the grinding and burnishing devices in alternate operative positions.
6. An apparatus for alternately grinding and burnishing saw-tooth wire on rollers, comprising means for removably supporting for rotation a roller to be operated upon, means for driving said roller, supporting brackets disposed adjacent to the ends of said roller, a movable head mounted for ro-

tation on said brackets and carrying a grinding roller and a burnishing brush, said grinding roller and burnishing brush being independently adjustable angularly of said head, independent means for clamping said roller and brush in adjusted positions, means for traversing and driving the grinding roller, means for driving the burnishing brush, gearing associated with said head for actuating the same, and adjustable means for regulating the angular movement of the burnishing brush thereby to facilitate insertion and removal of the roller.

7. An apparatus for grinding and burnishing saw-tooth wire on rollers, comprising means for supporting a roller for rotation in position to be operated on, means for driving said roller, supporting brackets disposed adjacent to the ends of the roller, gear wheels mounted for rotation on said brackets, supporting members pivoted for movement concentric with said gear wheels, a grinding device mounted for rotation in said supporting members, means for clamping said supporting members against movement independently of the gear wheels, means for traversing and driving said grinding device, independently movable supports pivoted for movement concentric with said gear wheels, a burnishing brush mounted in said supports, means for clamping said supports against movement independently of the gear wheels, adjustable means for limiting the movement of the burnishing brush supports, and means for driving the burnishing brush.

In testimony whereof I have signed my name to this specification.

JAMES DRONSFIELD.
